UNITED STATES PATENT OFFICE.

HAROLD S. LABOMBARDE, OF NASHUA, NEW HAMPSHIRE.

ELECTRIC COUNTER FOR BOX-MAKING MACHINES.

1,298,518.

Specification of Letters Patent. Patented Mar. 25, 1919.

Application filed June 10, 1918. Serial No. 239,174

To all whom it may concern:

Be it known that I, HAROLD S. LABOMBARDE, a citizen of the United States, and resident of Nashua, in the county of Hillsborough and State of New Hampshire, have invented certain new and useful Improvements in Electric Counters for Box-Making Machines, of which the following is a specification.

10 This invention relates to means for counting the product of a box-making machine, and refers particularly to devices adapted to be attached to machines of present make, so as to count the boxes as they issue from 15 the machine in flat folded condition.

One of the objects of my invention is to provide an improved device of the character stated which will perform its work accurately regardless of the size of the blanks 20 or boxes or the speed with which they pass.

Another object is to provide an improved device which not only enables an attendant to pick up assembled lots of the articles in predetermined quantities, for packing, but 25 also exhibits the total number of such lots.

With these and other objects in view, my invention consists in the construction and combination of parts substantially as hereinafter described and claimed.

30 Of the accompanying drawings—

Figures 1 and 2 are opposite side elevations of the machine, some unnecessary parts being omitted from Fig. 2.

Fig. 3 represents a sectional plan on line 35 3—3 of Fig. 1;

Fig. 4 represents a section on line 4—4 of Fig. 2;

Figs. 5 and 6 are, respectively, side and edge views of the insulating disk which 40 controls the circuit breaker.

Fig. 7 is a detail plan to illustrate the means for operating a mechanical counter;

Fig. 8 is a diagram to illustrate the electric circuit;

45 Fig. 9 is a view illustrating a modification.

The frame 20 of the mechanism is provided with lugs 21 forming sockets by means of which the frame can be hung on suitable 50 rods or parts of the box-making machine to bring the throat for the passage of the boxes hereinafter described to proper position,

The frame is adapted to be clamped in position by screws 22.

Vertically mounted in the frame is a shaft 55 23 having a ratchet 24, said ratchet omitting a few teeth to form a blank space 25 (Fig. 3). Secured to the upper end of the shaft is an arm 26, and secured to the lower end of the shaft is another arm 27 having a 60 pin 28.

An actuating pawl 29 for the ratchet is carried by an arm 30 having a sleeve bearing 31 mounted on the shaft 23. The outer end of the arm 30 is connected by a universal joint with a link 32 connected to a crank or wrist pin 33 projecting from one side of a pulley 34. Said pulley is adapted to be constantly rotated by a belt, from any part 65 of the box-making machine, so as to constantly swing the pawl 29. A detent pawl 35 carried by the lower end of a pin 36 secured to the frame prevents retrograde movement of the ratchet.

Mounted on the shaft 23 above the lower 75 portion of the frame is a sleeve 37 having an off-set upright lug 38. An arm 39 hereinafter referred to as the "kicker", is formed with a slot 40 (Fig. 1) through which screws 41 pass into a flat side face of the 80 sleeve 37, said slot and screws permitting the kicker arm to be adjusted in the direction of its length.

A spring 42, coiled about the shaft, is connected at one end to the lug 38 and at 85 the other end to a collar 43 pinned to the shaft. Carried by the shaft, between the spring and the kicker, are two oppositely radial pins 44, 45. These may be provided by a single pin passed through the shaft, 90 but are hereinafter referred to as two pins to aid in the description of the operation.

Mounted to slide vertically in the lower 95 bar of the frame is a stop pin 46 operated as hereinafter described and adapted to intermittently release and stop rotation of the kicker arm 39.

The operation of the mechanism as so far described is as follows:—The constant rotation of the pulley 34 causes the pawl 29, to 100 rotate the shaft 23 step by step until the space 25 of the ratchet arrives under said pawl. During the first portion of the rotation of the shaft, the kicker arm is carried

around until stopped by the vertical pin 46, the coiled spring 42 during this portion of movement tending to carry the lug 38 against the radial pin 44. During the continued rotation of the shaft, the said pin 44 leaves the lug 38 and the spring 42 is coiled up tighter or "wound up". By the time the opposite radial pin 45 arrives behind the vertical lug 38, as shown in Fig. 1, the blank space 25 of the ratchet arrives under the actuating pawl (see Fig. 3) and no further movement of the shaft occurs, the kicker arm remaining in contact with the stop pin 46 until the latter has been shifted down by the mechanism hereinafter described, said mechanism being constructed to cause the pin 46 to release the kicker so that the latter will act to shift to one side one box out of every predetermined number of boxes α that are being folded and delivered by the box-making machine. Preferably every fiftieth box is displaced as indicated at α , Fig. 3, so that an attendant can grasp boxes in bunches of 50 as said boxes arrive on the table belt hereinafter referred to. While for some purposes the coiled spring 42 might exert sufficient force to operate the kicker, I illustrate means for increasing such force, said means consisting of a spring 47 connected at one end to the pin 28 of arm 27 of the shaft, and at the other end to a screw 48 mounted in a bracket 49 connected to the frame. When the radial pin 44 is behind the lug 38 and the kicker is arrested by the stop pin, the shaft is in such a position of rotation that the spring 47 is under tension and tending to aid rotation of the shaft and kicker when the latter is released. The spring 47, acting as described, also insures rotation of the shaft 23 far enough to carry the blank space 25 of the ratchet far enough past the actuating pawl 29 to be ready for the next operation. Of course when the shaft 23 is later being rotated to bring the kicker into position for another operation and the arm 27 is moving around to the other side, the gradual rotation of the shaft by means of the actuating pawl engaging the ratchet will stretch said spring 47.

The upper arm 26 of the shaft, when said shaft automatically rotates to normal position immediately after operation of the kicker, engages an arm 50 (Fig. 7) of a counting mechanism 51 of any well known form such as a "Veeder" counter so that, when the parts are adjusted to cause the kicker to operate to displace every fiftieth box, the counter 51 will indicate each group of fifty boxes.

Secured to the shaft 23 between the kicker and the lower bar of the frame, is a cam collar 52 adapted to engage an arm 53 (Fig. 2) of a rock-shaft 54 to which a spring 55 is connected to cause the arm 53 to bear constantly yieldingly against the downwardly

facing surface of cam 52. The purpose of this rock-shaft will be explained herein-after.

To prevent the kicker arm, when released, from swinging around so rapidly as to pass over the stop pin 46 before the latter can have returned to its upper, arresting position, I provide a brake consisting of a leaf spring 56 secured to the base of the frame and normally projecting slightly above the plane of rotation of the lower edge of the kicker arm 39.

It is desirable that the kicker should be vertically adjustable so as to compensate for wear of its lower edge where it engages the stop pin 46, and also to render it certain that it will be accurately controlled by said stop pin. A convenient way to effect this adjustment is to mount the shaft 23 so that it can be vertically adjusted. As indicated in Figs. 1 and 2, the upper end of said shaft extends through an externally threaded bushing 57 having nuts 58 above and below the top bar of the frame whereby said bushing may be vertically adjusted, the shaft being so connected with the bushing, as by an annular groove, that when the bushing is adjusted the shaft also will be adjusted. As shown in Fig. 1 there is enough space between the underside of the lower bar of the frame and the arm 27 to permit of adjustment of the shaft sufficient for the purpose explained. The width of the ratchet and the actuating and detent pawls, and the width of the upper arm 26 are sufficient to enable the shaft to be vertically adjusted without passing beyond a position of co-operation with the other parts described.

The stop pin 46 is provided with a notch in the side of its lower end engaged by the short end of a lever 59 pivotally supported at 60 (Fig. 4), the long arm being acted upon by a spring 61 to act to normally hold the stop pin elevated, said long arm of the lever extending through a guiding bracket 62 and having its end engaging a notch in the side of the lower end of the armature 63 of a solenoid magnet 64 supported by a bracket 65 secured to the base of the frame.

Mounted on the lower bar of the frame is a block 66 which I refer to as the counter block. It is adjustable lengthwise of said lower bar by means of screws passing through a longitudinal slot 67 in said frame bar. This adjustment is provided for varying lengths of cartons or boxes being counted although I find in practice that adjustment is seldom necessary as the construction is such as to effect counting by the forward end or edge of each box or carton regardless of its length.

Secured to one side of the block 66 is the throat or chute 68 through which side portions of cartons or boxes pass as they are carried by the customary upper and lower

belts one of which is shown at 69 in Fig. 3 on their way to the table belt 70. To provide for varying thickness of cartons or boxes, said chute is vertically adjustable as by means of screws 71 passing through vertically slotted lugs 72 of said chute, into the block 66. This is to secure proper actuation, by the rapidly passing boxes or cartons, of the counting lever 73 the lower end 5 or finger 106 of which is adapted to extend across the exit of the chute so that each passing carton will lift the lever. Said lever is pivotally mounted on a shaft 74 mounted in the block 66, and is normally held in the 10 position shown in Fig. 1, by a spring 75. The two limits of throw of said lever are provided for by adjustable stop screws, one, 76, being supported by the block 66 and the other, 77, being carried by the rear end 15 of the lever.

Carried by the shaft 74 is a ratchet 78 which, when each fiftieth box is to be kicked out or laterally displaced will have fifty teeth. Said ratchet is actuated by a pawl 25 79 carried by the lever, a detent pawl being shown at 80.

The shaft 74 extends through the block 66 and at the other side of said block carries a disk 81 of insulating material said disk having a spiral groove in its periphery (Fig. 6), 30 one end of said groove terminating at a recess 83 in the periphery of the disk, said recess being formed abruptly at one side and inclined at the other side (see Fig. 5 in connection with Figs. 2 and 3). A lever 84, to make and break an electric circuit as hereinafter described, has a universally jointed and insulated support connection with the block 66 (Fig. 2). This joint and support 35 40 comprises a pin 85 supported by but insulated from the block 66, a small block 86 pivotally mounted on the pin 85, the lever 84 having a yoke pivoted to the upper and lower sides of said block 86. One arm of 45 the yoke is elongated at 87. The lever 84 has a platinum contact point 88 adapted to coöperate as hereinafter described with another platinum contact carried by a pin 89 projecting from the block 66. The lever 84 50 has a lug 90 which bears on the periphery of the cam disk 81, under the influence of a spring 91 connected at one end to the circuit lever 84 and at the other end to a pin 92 which is either of insulating material or 55 is insulated as to its support by the block 66.

The end of the long arm of the circuit lever 84 extends into a yoke-shaped block 93 (Fig. 3) of insulating material or insulated as to its support by the block 66. This 60 is to form a guide for the circuit lever which guide however will permit the lever to have some lateral movement as well as vertical movement, for the purpose hereinafter described.

65 The rock-shaft 54 has an arm 94 the upper

end of which is inclined over the arm 87 of the lever yoke, said arm 94 having its upper end covered with insulating material 95 so that no circuit will be established when actuation of the rock-shaft as hereinafter described causes said arm 94 to contact with the arm 87 to actuate the circuit lever to break circuit as hereinafter described.

70 Referring chiefly to Fig. 3 the bracket 65 has two binding posts 96, 97, the block 66 75 has a binding post 98, and the top bar of the frame 20 has a binding post 99 (Fig. 2). The block 60 and the bracket 65 are grounded as through the frame of the mechanism (and see Fig. 8).

When the disk 81 has been rotated fifty steps so as to permit the lug 90 of lever 84 to drop into the recess 83, the lever drops and causes point 88 to contact with pin 89. Then the circuit is completed through block 85 66 (from pin 89), the ground, bracket 65, winding of magnet 64 connected to said bracket, wire 100, post 96, wire 101 to any suitable battery 102, wire 103, binding post 97, wire 104, binding post 99, and wire 105 to 90 the binding post 98 of block 66. This completion of the circuit causes the armature of the magnet to actuate lever 59 to lower stop pin 46, thereby releasing the kicker and causing one of the folded boxes α which are 95 being carried along by the usual delivery belts of the folding machine (the upper one of such belts being indicated at 69 in Fig. 3) to be laterally displaced. Said one box will remain in such displaced position, as 100 indicated at α , when deposited on the table belt a portion of which is indicated at 70. The action of the kicker is so instantaneous as to render it practically impossible for more than one box at a time to be displaced, 105 thereby rendering the device far more practical than those which dislodge or displace two or three boxes at a time, because the exact number (such as 50) can be readily grasped and removed from the table belt 110 by the packing attendant.

The release of the kicker also releases shaft 23 which, under the influence of the impetus of the kicker caused by spring 42, and also spring 47, rotates far enough to not 115 only carry the blank space 25 of the ratchet beyond actuating pawl 29 so that the shaft will be then completely rotated by said pawl, but also causes the cam 52 of said shaft to act on arm 53 of rock shaft 54 to actuate the latter so that its other arm 94 will bring its insulated upper end 95 against and onto the arm 87 of the circuit lever 84, depressing said arm and also acting somewhat laterally against it, to raise the other end of said lever 120 and separate contact 88 from contact 89. This instantly breaks the circuit and renders the magnet inactive, and the spring 61 acts on lever 59 to raise the stop pin 46 in time 125 to prevent a second operation of the kicker 130

under the influence of its momentum. The 5 brake spring 56, being in the path of the lower edge of the kicker, renders a second operation absolutely impossible, and yet 10 yields to permit the kicker to pass over it to the stop, when the actuating pawl has continued to rotate shaft 23.

As has been stated, the arm 94 swings 15 the lever 84 laterally when the circuit is broken. This is to cause the lug 90 of the lever to be carried to position so that when the return of rock shaft 54 to normal position causes its arm 94 to release said lever, the said lug 90 will ride on the high part 20 of the spiral groove 82 in insulating disk 81, at one side of recess 83. No circuit-completing contact at 88, 89 can then again be made until the disk 81 has made another rotation, caused by the actuation of the counting lever 25 73 by the successively passing boxes.

While the counting lever or finger might 30 be made of a single piece, I prefer to make it as shown in Figs. 1 and 3, in which the lever proper, 73, has a spring finger 106 secured to an off-set portion thereof by screws 107. And the lower wall of the chute or 35 box-guide 68 is formed with a finger 108 to so support the passing box as to render it certain that the box can not so yield down- 40 wardly as to fail to operate the counting lever far enough to rotate the ratchet 78 one tooth.

In practice, a suitable casing is provided 45 for the block 66 and the parts carried thereby to exclude dust from such parts as the ratchet 78 and cam-grooved disk 81 the operation of which might be interfered with by the dust. I have not illustrated such casing 50 because it would obstruct the showing of the operative parts.

To avoid any possibility of overthrow of ratchet 78 and cam disk 81, I may employ a 55 brake such as a leaf spring 109 (Fig. 5) mounted to bear against said disk.

I do not limit myself to the employment 60 of a kicker of the kind hereinbefore described, as the displacer of the boxes at pre-determined intervals. For instance, referring to Fig. 9 in which the box-carrying belts 69 are shown in section, I may employ a suitably mounted pad 130 with which another pad 131 is adapted to coöperate, said pad 131 being carried by a lever 132 pivotally supported at 133 and having an armature 134, operated by a magnet 135 which is in a circuit such as the magnet 64 herein-before described. With this structure, the 65 same completion of a circuit as already described, causes the pad 131 to momentarily pinch the edge of a passing box *a* between it and pad 130 and then release it. The pads are preferably of friction material such as rubber. As the carrier belts 69 travel continuously, the momentary arresting of a side 70 or edge portion of a folded box by the pinch-

ing action described, causes the box to be turned askew.

Having now described my invention what I claim is:

1. A counting device for attachment to a 70 box making machine, comprising normally ineffective means for displacing boxes out of their normal path of travel, electrically controlled mechanism for effecting the operation of said displacing means, a movable finger 75 normally extending entirely across said path of travel, and means controlled by said finger for effecting the operation of said electrically controlled mechanism when a pre-determined number of the boxes have 80 passed.

2. A counter of the character described, comprising a guide for the successive passage of separated articles, a ratchet, means controlled by the passage of each article for 85 actuating the ratchet, said means including a movable finger normally extending entirely across said guide, electrically-controlled means for displacing articles out of their normal path of travel, a make and 90 break device in the circuit of said electrically-controlled means, and means controlled by the ratchet for operating said make and break device.

3. A counter of the character described, 95 comprising a guide for the successive passage of separated boxes, a movable finger normally extending entirely across said guide in position to be actuated by each passing box, a ratchet operated by said finger, electrically controlled mechanism for intermittently displacing boxes out of their normal path of travel, and means operated by said ratchet controlling the circuit of 100 said electric mechanism.

4. In a counter of the character described, a shaft having a ratchet provided with a blank space, an actuating pawl engaging the ratchet, means for continuously operating said pawl, a spring tending to rotate 110 said shaft, a box kicker carried by said shaft, a stop positioned to arrest the kicker and shaft when said pawl is on the blank space of the ratchet, and means controlled by the passage of boxes to effect the release 115 of the kicker and shaft after the passage of a pre-determined number of boxes.

5. In a counter of the character described, a shaft having a ratchet provided with a blank space, a pulley having a crank pin, 120 an arm mounted on the shaft and having an actuating pawl engaging the ratchet, a link connecting said crank pin and arm, a spring tending to rotate said shaft, a box kicker carried by said shaft, a stop positioned to 125 arrest the kicker when said pawl is on the blank space of the ratchet, and means controlled by the passage of boxes to effect the release of the kicker after the passage of a pre-determined number of boxes.

6. In a counter of the character described, a shaft having a kicker, a stop for said kicker, means for automatically rotating the shaft until the kicker is arrested by said stop, and means controlled by the passage of boxes to shift said stop to release the kicker after the passage of a pre-determined number of boxes.

7. In a counter of the character described, a shaft having a kicker, a stop for said kicker, means for automatically rotating the shaft until the kicker is arrested by said stop, means for adjusting the vertical relationship of the kicker and stop, and means controlled by the passage of boxes to shift said stop to release the kicker after the passage of a pre-determined number of boxes.

8. In a counter of the character described, a shaft having a kicker loosely mounted thereon and connected thereto by a spring, a stop for said kicker, means for automatically rotating the shaft until the kicker is arrested by said stop, and means controlled by the passage of boxes to shift said stop to release the kicker after the passage of a pre-determined number of boxes.

9. In a counter of the character described, a shaft having a kicker loosely mounted thereon and connected thereto by a spring, said kicker having a lug and the shaft having a pair of radial pins adapted to alternately coat with said lug, a stop for the kicker, means for automatically rotating the shaft until the kicker is arrested by said stop, and means controlled by the passage of boxes to shift said stop to release the kicker and shaft after the passage of a pre-determined number of boxes.

10. In a counter of the character described, a movable stop, an electromagnet for controlling said stop, a kicker normally held in inoperative position by said stop, and means controlled by the passage of boxes to cause the magnet to shift the stop to release the kicker and laterally displace one box after the passage of a pre-determined number of boxes.

11. In a counter of the character described, a shaft having a ratchet provided with a blank space, an actuating pawl engaging the ratchet, a kicker carried by said shaft, a stop to arrest the kicker when the pawl rides on the blank space of said ratchet, a spring connected with the shaft to partially rotate it to carry said blank space beyond the actuating pawl when the stop releases the kicker, and means controlled by the passage of boxes to shift said stop to release the kicker after the passage of a pre-determined number of boxes.

12. A counting device for attachment to a box making machine, comprising normally ineffective means for displacing boxes out of their normal path of travel, electrically controlled mechanism for effecting the opera-

tion of said displacing means, means including a movable finger normally extending entirely across said path of travel for effecting the operation of said electrically controlled mechanism when a pre-determined number of the boxes have passed, and means for counting the number of operations of the displacing means.

13. In a counter of the character described, a movable stop, an electromagnet for controlling said stop, a kicker normally held in inoperative position by said stop, means controlled by the passage of boxes to cause the magnet to shift the stop to release the kicker after the passage of a pre-determined number of boxes, and means for counting the number of operations of the kicker.

14. In a counter of the character described a shaft having a ratchet provided with a blank space, an actuating pawl engaging the ratchet, a kicker carried by said shaft, a stop to arrest the kicker when the pawl rides on the blank space of said ratchet, a spring connected with the shaft to partially rotate it to carry said blank space beyond the actuating pawl when the stop releases the kicker, means controlled by the passage of boxes to shift said stop to release the kicker after the passage of a pre-determined number of boxes, an arm carried by said shaft, and a counter adapted to be actuated step by step by said arm.

15. In a counter of the character described a shaft having a kicker, a stop for said kicker, a cam carried by said shaft, an electromagnet for controlling said stop, means controlled by the passage of boxes to cause the magnet to shift the stop to release the kicker after the passage of a pre-determined number of boxes, and means actuated by said cam to break the circuit of the electromagnet when the kicker is released.

16. In a counter of the character described, a shaft having a kicker, a stop for said kicker, a cam carried by said shaft, an electromagnet for controlling said stop, means controlled by the passage of boxes to cause the magnet to shift the stop to release the kicker after the passage of a pre-determined number of boxes, a rock shaft having two arms one of which is engaged and actuated by said cam, and a circuit breaker adapted to be actuated by the other arm of the rock shaft when the kicker is released.

17. In a counter of the character described, a shaft having a kicker, a stop for said kicker, means for automatically rotating the shaft until the kicker is arrested by said stop, a spring connected to said shaft to partially rotate it toward said stop, a brake for said kicker, and means controlled by the passage of boxes to shift said stop to release the kicker and shaft after the passage of a predetermined number of boxes.

18. In a counter of the character described,

- a shaft having a kicker, a stop for said kicker, means for automatically rotating the shaft until the kicker is arrested by said stop, means for adjusting the kicker to alter 5 its plane of rotation relatively to said stop, and means controlled by the passage of boxes to shift said stop to release the kicker and shaft after the passage of a pre-determined number of boxes.
- 10 19. In a counter of the character described, a frame, a shaft mounted in said frame and having a kicker, a stop for said kicker, an electromagnet for controlling said stop, means controlled by said shaft for breaking 15 the circuit of the magnet, a block mounted in the frame and adjustable relatively to the shaft, and means including a circuit breaker carried by said adjustable block to cause the magnet to shift the stop when a pre-determined number of boxes have passed.
- 20 20. In a counter of the character described, a chute for the passage of boxes, a movable finger normally extending entirely across said chute in position to be actuated 25 by each passing box, normally ineffective means for displacing boxes out of their normal path of travel, electrically controlled mechanism for effecting the operation of said displacing means, and means for effecting the operation of said electrically controlled mechanism when said finger has been actuated a pre-determined number of times.
- 25 21. In a counter of the character described, a chute for the passage of boxes, a finger in position to be actuated by each passing box, normally ineffective means for displacing boxes out of their normal path of travel, electrically controlled mechanism 30 for effecting the operation of said displacing means, and means for effecting the operation of said electrically controlled mechanism when said finger has been actuated a pre-determined number of times, said last- 35 mentioned means including a ratchet, a lever carrying said finger and having a pawl to actuate the ratchet, a circuit controlling member, and means whereby the circuit controlling member is actuated once for 40 each rotation of the ratchet.
22. In a counter of the character described, a vertically adjustable chute for the passage of boxes, a movable finger normally extending entirely across said chute 45 in position to be actuated by each passing box, normally ineffective means for displacing boxes out of their normal path of travel, electrically controlled mechanism for effecting the operation of said displacing 50 means, and means for effecting the operation of said electrically controlled mechanism when said finger has been actuated a pre-determined number of times.
23. In a counter of the character described, a chute for the passage of boxes, 55 a lever provided with a finger normally extending entirely across the path of boxes moving through the chute, said lever having a pawl, a shaft having a ratchet engaged by said pawl, normally ineffective means for displacing boxes out of their normal path when leaving the chute, electrically controlled mechanism for effecting the operation of said displacing means, and means controlled by the rotary position of 60 said shaft for effecting the operation of said electrically controlled mechanism.
24. In a counter of the character described, a shaft having a disk provided with a recess, means for rotating the shaft step-by-step by the passage of boxes, normally ineffective means for displacing boxes out of their normal path of travel, electrically controlled mechanism for effecting the operation of said displacing means, a lever bearing on said disk, and means whereby the electric circuit is closed when the recess in said disk arrives opposite said lever.
25. In a counter of the character described, a shaft having a disk provided with a recess and a spiral groove in its periphery, means for rotating the shaft step-by-step by the passage of boxes, normally ineffective means for displacing boxes out of their normal path of travel, electrically controlled mechanism for effecting the operation of said displacing means, a lever having a projection bearing on the periphery of said disk, means for closing the electric circuit when said projection is in the recess of the disk, and means whereby said circuit is interrupted while said projection is in the groove of the disk.
26. In a counter of the character described, a shaft having a disk provided with a recess and a spiral groove in its periphery, means for rotating the shaft step-by-step by the passage of boxes, normally ineffective means for displacing boxes out of their normal path of travel, electrically controlled mechanism for effecting the operation of said displacing means, a universally mounted lever having a projection bearing on the periphery of said disk, means for closing the electric circuit when said projection is in the recess of the disk, and means whereby said circuit is interrupted while said projection is in the groove of the disk.
27. In a counter of the character described, a shaft having a disk provided with a recess and a spiral groove in its periphery, means for rotating the shaft step-by-step by the passage of boxes, normally ineffective means for displacing boxes out of their normal path of travel, electrically controlled mechanism for effecting the operation of said displacing means, a universally mounted lever having a projection bearing on the periphery of said disk,

ing on the periphery of said disk, means for closing the electric circuit when said projection is in the recess of the disk, means whereby said circuit is interrupted while 5 said projection is in the groove of the disk, and means controlled by the box displacing means for actuating said lever to shift its projection from the recess of the disk to the peripheral groove thereof.

10 28. A counting attachment for box-making machines, comprising a guide for the successive passage of boxes, a ratchet, means

controlled by the passage of each box for actuating the ratchet, an electric circuit, means operated by said ratchet for controlling said circuit, a magnet in said circuit, a lever having an armature at one end and a pad at the other end, and a fixed pad, the two pads being in position to grasp a portion of a passing box when the circuit 20 of the magnet is closed.

In testimony whereof I have affixed my signature.

HAROLD S. LABOMBARDE.
